United States Patent Office

Des. 189,809
Patented Feb. 28, 1961

189,809

ZIPPERED RING BINDER

Seymour Mace Cole, Glencoe, and Paul I. Dale, Wilmette, Ill., assignors to Feldco, Inc., Chicago, Ill., a corporation of Illinois

Filed Mar. 21, 1960, Ser. No. 59,808

Term of patent 14 years

(Cl. D6—2)

Fig. 1 is a top perspective view of a zippered ring binder, showing our new design;

Fig. 2 is a bottom plan view thereof on slightly reduced scale; and

Fig. 3 is a sectional view thereof taken on the line 3—3 of Fig. 1.

We claim:

The ornamental design for a zippered ring binder, as shown.

References Cited in the file of this patent

UNITED STATES PATENTS

D. 118,191	Trussell	Dec. 19, 1939
2,018,551	Freling	Oct. 22, 1935
2,716,985	Wolf	Sept. 6, 1955

OTHER REFERENCES

Horder's, Inc., "Office Supplies, Furniture and Business Equipment," catalog, © 1952, page 174, lower left zipper ring binders.

Sears, Roebuck and Co., Chicago, Fall and Winter 1959, Catalog No. 219, page 1027, items A and B.